Attorney.

UNITED STATES PATENT OFFICE.

FREDERICK ELLIS WARD, OF EAST ORANGE, NEW JERSEY, ASSIGNOR TO CROCKER-WHEELER COMPANY, OF AMPERE, NEW JERSEY, A CORPORATION OF NEW JERSEY.

CONTROLLER CHECK.

Application filed June 1, 1922. Serial No. 565,094.

To all whom it may concern:

Be it known that I, FREDERICK ELLIS WARD, a citizen of the United States of America, and a resident of East Orange, 5 county of Essex, and State of New Jersey, with a post-office address Box 57, Ampere, New Jersey, have invented certain new and useful Improvements in Controller Checks, of which the following is a specification.

10 This invention relates to a check for a hand operated electric motor controller or starting switch wherein there are one or more intermediate positions between the off position and the full running position where 15 the circuits to the motor are protected by the introduction of inductance or resistance, and at which it is necessary to pause in starting the motor until sufficient speed has been reached to warrant the removal of such inductance or resistance. Such a switch is 20 shown in United States patent application Serial No. 475,785, filed June 7, 1921.

The object of this invention is to provide a check for the switch at such intermediate 25 position, and to provide means operated through the controller or switch handle which requires its movement in a different direction when the check is reached in order to release the switch for further movement. 30 Inadvertent passing of this position without pausing is thereby prevented. The construction is also such that on returning from the running position to the off position the movement is not interrupted by the check.

35 In the accompanying sheet of drawings which forms a part of this specification;

Figure 1 is a front view of a portion of a motor starting switch, the cover of the casing being omitted, which shows a crank handle and check associated in accordance with 40 this invention,

Fig. 2 is a side view of the same,

Fig. 3 is a vertical section on the line III—III of Fig. 1, the switch being in full 45 running position,

Fig. 4 is a vertical section on the line IV—IV of Fig. 1, the switch being in the checked position, and

Fig. 5 is a section on the oblique line 50 V—V of Fig. 4 in projected position from Fig. 4.

A switch member 10, rotatable about an axis A—A, carries cylindrical contact segments 11 which contact in operated positions 55 of the switch member with fingers 12, 12.

The contacts are so shaped and positioned and the connections to the cylindrical contacts and fingers are such that current at a safe potential for starting the motor is admitted in an intermediate position, and the 60 full potential for the motor at its regular running speed is admitted in the final position of the switch. A casing 13 encloses the switch. Mounted in the side wall of the casing is a bearing 14 in line with the axis of 65 the switch. A shaft 15 passes through the bearing and a connecting member 16 is attached to the inner end of the shaft and couples it to the switch member. This connecting member carries an armature 17 which is 70 brought against an electromagnet 18 and held thereby when the switch is in its fully operated and closed position. A spring 19 returns the switch to open position when the current is cut off from the magnet. 75

Outside of the casing the shaft has an arm 20, and pivoted to this arm by a pin 21 is a handle member which consists of a channel-shaped part 22 and a handle 23 riveted to one end of the channel-shaped 80 part. The channel-shaped part has a bent-over lug 22^a projecting under the arm which is notched to permit a limited outward movement of the channel-shaped part in the plane of the controller axis and preferably in the 85 direction of its axis. A spring 24 presses the handle member outward from the arm. The sides of the channel-shaped part engage the sides of the arm so that force applied through the handle to operate the 90 switch is communicated through the arm and not through the pivot pin. A check 25 is pivoted to a block 26 which is riveted to the inner side of the casing and the check normally projects through a hole in the 95 casing into the path of the arm so as to check the switch at the starting position when it is being moved toward full running position. A spring 27 holds the check in its normal position. The top of the check 100 is beveled at 25^a and the under side of the arm is beveled at 20^a as shown in Fig. 5, so that on return movement the arm will depress and pass over the check and not be stopped thereby. The channel-shaped 105 part has a prong 28 so positioned as to be over the check when the arm is in contact with the face of the check so that if the handle member is then depressed the check will be pushed out of the path of the arm 110

and further movement of the switch toward full running position will be permitted. Both operation of the switch and disengagement of the check are effected by movement of the same handle, but by movements at right angles to each other so that one is not a natural continuation of the other and can succeed one another only with a pause.

Initial operation of the switch from the off to the starting position is preferably effected without depressing the handle, for if the handle is depressed during this part of the movement the prong instead will come in contact with the face of the check and then the handle will have to be lifted to bring the prong on top of the check and again depressed before further progress can be made toward full running position.

I claim,—

1. In a controller, an arm for operating the controller, a handle member for operating the arm having a movement with the arm and also in the plane of the controller axis, and a movable check normally in the path of the arm and constructed to be en-

gaged by the handle member when the arm is in contact with the check and to push the check out of the path of the arm.

2. In a controller, an arm for operating the controller, a handle member pivoted to the arm for operating the arm having a movement with the arm and also in the plane of the controller axis, and a movable check normally in the path of the arm and constructed to be engaged by the handle member when the arm is in contact with the check and to push the check out of the path of the arm.

3. In a controller, an arm for operating the controller, a handle member with a channel-shaped part pivoted to the arm and the sides of which engage the arm for operating the arm having a movement with the arm and also in the plane of the controller axis and a movable check normally in the path of the arm constructed to be engaged by the handle member when the arm is in contact with the check and to push the check out of the path of the arm.

FREDERICK ELLIS WARD.
